PACKING CASE

Charles Gaston Coulbeaux, Levallois-Perret,
FranceApplication March 28, 1930, Serial No. 439,556,
and in France January 14, 1930

2 Claims. (Cl. 217—12)

Types of packing cases are already known which can be quickly and easily dismantled and reassembled as many times as may be desired without any risk of being damaged or destroyed 5 for a long time, the assembling of the panels of such cases being effected without the use of nails.

In certain of these cases, the panels engage with one another by means of grooves provided along the edges of certain panels and with which 10 the edges of the adjoining panels engage. These grooves may be constituted for instance by rods held at a certain distance from the edges of the panels.

When the various panels are engaged with one 15 another, they are held assembled as a rule by putting one or more wires round the case thus constituted.

When the case is dismantled, the various panels of the same can be stacked on one another.

The present invention relates to a case, the various panels of which can also be assembled together and once the case is dismantled can be stacked on one another. But in this type of 25 case that can be dismantled, the various panels are assembled together by means of projecting tenons provided on the edges of the panels, in the plane of the latter, and engaging with mortises provided in the adjoining panels.

Each tenon may be constituted by a projection made out of the material of the panel or secured to it, and reinforced outside preferably by means of a fitting constituted for instance by stamped out metal plate, the toothed edges 30 of which engage with the panel.

Each mortise may be constituted by a recess provided in the edge of the panel and trimmed or covered outside preferably by means of a fitting firmly secured to the said panel.

The fitting in question may be constituted by a simple sheet or band of metal held by means 40 of clips or fasteners secured to the panel. It may be constituted also by a piece of metal, the ends of which given a suitable shape and stamped out, have toothed or serrated edges engaging with the panel.

Several constructions according to the invention are illustrated by way of example in the accompanying drawings, without being in any 50 way limitative.

In the said drawings:

Figure 1 shows in perspective the various panels of the case separately.

Figure 2 shows in perspective the assembled 55 case.

Figure 3 is a perspective view of a mortise with its fitting.

Figure 4 is a section of a tenon engaging with its mortise.

Figures 5 and 6 are two modified constructions of mortise and tenon. 60

The case comprises a bottom 1 and four sides 2 (equal or unequal in twos) each constituted for instance by wooden boards or planks joined together by bars 3. A cover 4 also constituted 65 for instance by boards or planks connected together by bars 5, engages with the case thus constituted, between the projecting portions of the bars 3 of the lateral panels.

In the bottom edge of each of the large sides 70 2 is provided a mortise 6 trimmed or covered outside by a hoop iron 7, the widened ends of which are turned over and provided with teeth 8 which engage with the wood of the panel 2. Into each of these mortises 6 thus trimmed with 75 a metal band securely fixed to the side 2 of the case, can penetrate a tenon 9 secured to the bottom 1 of the latter and reinforced by a stamped out piece of sheet metal 10, the turned down edges of which are also provided with teeth 11 80 which engage with the wood of the bottom 1.

In the same way, the small sides 2 of the case comprise each three mortises 6 with which engage tenons similar to the tenons 9 and secured to the bottom 1 and to the large sides 2 of the case. 85

The tenons 9, instead of being constituted by a projecting portion of the edge of the board strengthened subsequently by a piece of metal sheet, may be constituted also (Figure 6) by a put-on key 12 of wood or other material held in place 90 by a metal clip 13 with toothed edges driven into the walls of the wood of the panel.

In the same way, the mortises 6 could be trimmed with a piece of hoop iron 14 (Figure 5) held in place at its ends by put-on metal brackets 95 or clips 15 with toothed edges engaging with the wood.

It goes without saying that instead of providing on each edge of the bottom or of the sides of the case, only one tenon or only one mortise, it is possible to provide several of them arranged one behind another. 100

In the same way, the sides of the case may comprise tenons engaging with mortises in the bottom and/or in the other sides. 105

Instead of providing metal covering only at the point of the tenons and of the mortises, such coverings could be provided also all round each of the panels of the case so as to give greater strength to the latter. 110

According to the thickness of the wood panels constituting the sides of the case, the teeth of the parts 7, 10, 13, 15 may be made of a correspondingly greater or smaller length.

5 The method of assembling the case will be readily understood.

First take the bottom 1 and put in place successively each of the sides 2 introducing the tenons 9 of the bottom and of the sides into the corresponding mortises 6 of the opposite panels. This having been done, assemble the whole for instance by means of pieces of hoop iron or of iron wires 16 passed preferably into the mortises 6, against the inner wall of the hoop irons 7 used for the 15 trimming. The number of the assembling hoop irons or wires thus utilized may vary at will. These hoop irons or wires are finally tightened and secured to the panels by any desired well known means. Once the case has been filled, it is 20 merely necessary to put in place the cover which may also be secured by means of hoop irons or iron wires 17 or in some other manner.

To dismantle the case, it is sufficient to cut the wires or hoop irons which hold the panels together whereupon the latter can be easily detached from one another and stored with the panels of other cases in a limited space by superposing them or simply placing them side by side.

It will be seen that these cases which do not comprise any assembling by nails, will not deteriorate during their successive dismantling and reassembling, so that they have a long life.

It will be understood that this case may be made 80 of any desired size and if desired of materials other than wood.

I claim:

1. In a case, a plurality of detachable wood panels forming the sides and bottoms of said case, some of said panels provided with tenons and adjacent panels having cooperating mortises, the mortises being constituted each by a notch made in the edge of the panel and closed by a metallic strip going deep into the wood at its ends beyond the ends of the notch, the breadth of the notches being equal to the thickness of the panels. 85 90

2. In a case, a plurality of detachable wood panels forming the sides and bottoms of the case, some of said panels provided with tenons and adjacent panels having cooperating mortises, the mortises being constituted each by a notch made in the edge of the panel and closed by a metallic strip secured to said edge at its ends by teeth going into the wood at a distance from the edge, 100 the breadth of the notches being equal to the thickness of the panel. 95 100

CHARLES GASTON COULBEAUX.
